UNITED STATES PATENT OFFICE

WERNER SCHWAN, OF DALLAS, TEXAS

GAS BURNER

Application filed August 1, 1928. Serial No. 296,775.

This invention relates to new and useful improvements in gas burners.

The invention has particularly to do with that type of burner which is operated under a mechanical draft.

One object of the invention is to provide a gas burner of the type described, whereby an accurate control of the amount of air necessary for proper combustion of a given amount of gas is had and a thorough and intimate mixture of the air and gas is produced in the combustion chamber.

A particular object of the invention is to provide means for delivering the gas into the path of the air at right-angles to the line of travel of said air and not only prior to combustion but at a point removed from the point of combustion, whereby a thorough gaseous mixture is produced.

Another object of the invention is to provide a burner tip, whereby ignited gas or a flame is provided contiguous to the discharge end of the burner, thus assuring more complete combustion and also guarding against extinguishing of the flame, either by excessive draft or an impoverished gas supply.

A still further object of the invention is to provide means for delivering gas transversely or radially of the path of the air and at the same time deflecting both the air and gas against the walls of the air tube, whereby a more thorough mixture of the air and gas is carried out.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is a plan view of a burner assembly constructed in accordance with the invention,

Fig. 2 is an enlarged cross-sectional view taken on the line 2—2 of Fig. 1,

Fig. 3 is a similar view showing the damper open,

Fig. 4 is an enlarged longitudinal sectional view of one of the burner nozzles.

Fig. 5 is an enlarged cross-sectional view taken on the line 5—5 of Fig. 4,

Fig. 6 is an enlarged horizontal cross-sectional view taken on the line 6—6 of Fig. 4,

Fig. 7 is an end elevation of the burner,

Fig. 8 is a side elevation of a burner and blower showing an automatic controlling means,

Fig. 9 is an end elevation of the same, 60 the blower being omitted, and

Fig. 10 is an enlarged horizontal cross-sectional view on the line 10—10 of Fig. 8.

In the drawings the numeral 10 in Fig. 1 designates a blower which may be driven by 65 an electric motor 11 or any other suitable means, and from which a tubular header 12 extends. The header is closed by an end cap 13 and may be of any suitable length according to the number of burners which are to be 70 connected thereon. The invention contemplates the use of a plurality of burners, as is shown in Fig. 1, or a single burner, as is shown in Figs. 8, 9 and 10 and which will be 75 more particularly described.

Referring to Fig. 1 it will be noted that the header 12 is provided with a T 14 for each burner, said tees being suitably spaced and permitting the burners to be connected at right-angles to the header. Each burner includes, as is shown in detail in Figs. 4 to 7 inclusive, a mixing T 15. The T is internally screw-threaded at each end and an elongated mixing tube 16 is screwed into one end of said T. A nipple 17 is screwed into 85 the opposite end of the T and this nipple may be screwed into the T 14 to connect the burner with the header 12. An important feature 80 of the T is an elbow 18 cast integral therewith and extending axially and radially of said T. A gas supply pipe 19 is screwed into the outer end of the elbow and a relatively small nipple 20 is screwed into the inner end of the elbow so as to extend axially of the tube 16.

Air is delivered to the T 15 through the nipple 17 while gas is delivered to the elbow 18 by the pipe 19. While the air is delivered from the blower 10, it is to be understood 90 that it is not under a great pressure. Very 95

Air is delivered to the T 15 through the nipple 17 while gas is delivered to the elbow 18 by the pipe 19. While the air is delivered from the blower 10, it is to be understood 100 that it is not under a great pressure. Very

successful results are had where the pressure of the air blowing through the tube 16 is approximately two ounces or less.

On the end of the nipple 20 I mount a deflector 21 which consists of an elongated tubular body having a flat circular head 22 closing the end of the body and projecting radially beyond the same. Flush with the inner side of the head the deflector is provided with a plurality of radial ports 23.

10 The gas delivered to the deflector strikes the flat head and is thus deflected radially through the ports 23 at right angles to the path of the air flowing through the tube 16.

15 It will be noted that the head 22 of the deflector projects radially beyond the body thereof and thus extends into the path of the air passing along the tube 16. This will cause a deflection of both the air and gas, whereby it will be thrown into contact with the inner wall of the tube from which it will rebound, thus setting up an oscillation of the fluid currents which will effect a more thorough mixture. The deflector which also has the function of a spreader is located near the central portion of the tube and at some distance from the discharge end of said tube, which will give the air and gas full opportunity to commingle and produce the proper mixture; however, the deflector is not located far enough from the discharge end of the nozzle as to allow undesirable conditions before being ignited.

20 The gas being delivered transversely of the path of the air will cause a more thorough mixing and the production of a highly combustible gaseous fluid. The volume of the air will be many times that of the gas, therefore, making for economy as well as efficiency.

25 The air being under a mechanical draft will tend to carry the gas away from the deflector, thus preventing back pressure when a low pressure of gas is supplied. Although the air is introduced by a fan or other blower it need not be under a high pressure because successful tests have been made where the air was under pressure on only one-half an ounce.

30 On the outer end of the tube a nozzle head 24 is screwed and this head has an internal bore equal in diameter to that of the tube. The end of the head which constitutes the tip of the burner, is slightly reduced at 25 and a tip ring 26 is inserted in the reduced end of the head. The ring comprises an inwardly displaced annular flange 27 and a beveled inner bell 28, which converges from the wall of the head to the inner wall of the flange. The flange 27 in conjunction with the reduced annular tip of the head provides an annular space or chamber 29 and radial ports 30 extending through the base of the flange permit the gaseous mixture to enter said chamber.

35 The gaseous mixture produced at the de-

flector 21 must flow through the tube 16 and head 24 before discharging through the ring 26 and is thus given full opportunity to develop into an intimate and highly combustible mixture. When the flame is ignited it 70 will be projected from the end of the head into the fire box, but a ring flame will burn contiguous to the chamber 29. This is an important feature because usually the flame is not ignited for several inches from the tip 75 of the burner and excessive drafts or impoverished gas supply would cause the ordinary flame to become extinguished; however, by provision of the ring flame this would be avoided. The bell 28 tends to converge and compress the gaseous fluid and reduces the resistance offered to the discharge of the same.

80 In Figs. 1, 2 and 3 I have shown a damper 31 mounted in the nipple 17. This damper is shown closed in Fig. 2 and open in Fig. 3. It is obvious that by regulating the damper 85 the volume of air flowing through the nipple 17 may be regulated and this is particularly important where more than one burner 90 is connected with a single header. The damper may be used or it may be omitted.

85 In Figs. 8 to 10, inclusive, I have shown the T 15 connected with a nipple 32, which in turn is connected with an air blower 33. 95 A damper housing 36 is connected in the gas pipe 19 and includes a damper 37 mounted on a crank-shaft 38. The crank-shaft 35 has a plurality of spaced apertures 39 for receiving a bolt 40 engaging in 100 spaced apertures 41 in a link 42, which is connected with a crank 43 mounted on a rock-shaft 44 journaled on the nipple 32.

95 It will be seen that by rocking the shaft 44 and swinging the crank 43 the damper 105 34 will be actuated by the parts 35 and 42. By adjusting the bolt 40 in the apertures 39 and 41, the relative throw of the damper will be varied in proportion to the swing of the crank 43.

110 A pitman 45 is also pivoted to the crank 43 and has a plurality of apertures 46 at its opposite end for receiving a bolt 47 engaging in spaced apertures 48 in the crank shaft 38, whereby the damper 37 may be 115 swung and the amplitude of its swing controlled in proportion to the swing of the damper 34. By reason of the adjustments the two dampers may be set to supply any given amount of air and gas, as is obvious, 120 and when the shaft 44 is operated the control of the air and gas supplies becomes automatic.

125 For operating the shaft 44 a lever 49 is fastened thereon and carries a weight 50 to which a flexible connection 51 is attached. The connection 51 may be connected with any kind of a-controlling device so that by a manipulation of said connection the supply of air and gas is automatically proportioned. 130

Various changes in the size and shape of the different parts, as well as modifications and alterations, may be made within the scope of the appended claims.

What I claim, is:

5 1. In a gas burner, a mixing tube, a gas supply pipe extending within the tube, an air supply pipe also connected with the tube, a pivoted damper within the gas supply pipe 10 having an operating arm, a pivoted damper within the air supply pipe having an operating arm, an operating lever, and separate connections from said lever to said arms for 15 operating the dampers in a fixed ratio of movement, and means for varying the point of attachment of said connections to said arms for changing said ratio.

2. In a gas burner, a mixing tube, a gas supply pipe connected with the tube, an air supply pipe also connected with the tube, a 20 rotative gas control valve connected in the gas pipe, an air control valve connected in the air pipe, each valve having a crank, a link connected with the crank of the air valve, a pitman connected with the crank of the 25 gas valve, a rock shaft to which said link and pitman are connected for joint operation to move one valve in a fixed ratio of movement to the other valve, and adjustable means 30 upon said link and pitman for changing said ratio of movement.

3. In a gas burner, a T having a reduced elbow extending radially and axially thereof, a mixer tube connected to one end of the T, an air supply pipe connected to the opposite 35 end of the T, a deflector within the tube connected with the elbow and disposed laterally to deflect air and gas into contact with the tube and having a single series of radial ports 40 at the inner face of the deflector, and a head mounted on the outer end of the tube and having a reduced tip located remote from 45 said ports to form a mixing chamber beyond the deflector.

4. A gas burner including a mixing tube, an air supply conduit communicating with the inlet end of the tube, a gas supply pipe contained within the tube having a circumferential series of gas discharge ports located 50 inwardly of and relatively remote from the discharge end of the tube, and a deflector plate provided on the end of the gas supply pipe adjacent to and beyond the discharge ports thereof, the deflector plate being greater 55 in area than the cross sectional area of the discharge end of the gas supply pipe.

5. A gas burner including a mixing tube, an air supply conduit communicating with the inlet end of the tube, a gas supply pipe 60 contained within the tube having a circumferential series of gas discharge ports located inwardly of and relatively remote from the discharge end of the mixing tube, and a deflector plate provided on the end of the gas 65 supply pipe adjacent to and beyond the dis-

charge ports thereof, the deflector plate being greater in area than the greatest cross sectional area of the gas supply pipe.

6. A gas burner including a mixing tube, an air supply conduit communicating with the inlet end of the tube, a gas supply pipe contained within the tube having a circumferential series of gas discharge ports located 70 inwardly of and relatively remote from the discharge end of the mixing tube, and a deflector plate provided on the end of the gas supply pipe adjacent to and beyond the discharge ports thereof, the deflector plate being greater in diameter than the diameter of the largest portion of the gas supply pipe.

7. A gas burner including a mixing tube, an air supply conduit communicating with the inlet end of the tube, a gas supply pipe contained within the tube having a circumferential series of gas discharge ports located 75 inwardly of and relatively remote from the discharge end of the mixing tube, and a deflector plate provided on the end of the gas supply pipe adjacent to and beyond the discharge ports thereof, the peripheral margin 80 of the deflector plate extending beyond the outer periphery of the adjacent end portion of the gas supply pipe.

In testimony whereof I affix my signature.
